CLAIM

The ornamental design for a superheat calculator meter face plate, as shown and described.

DESCRIPTION

FIG. 1 is a front plan view of the superheat calculator meter face plate showing my new design;

FIG. 2 is a side view thereof taken from the left side of FIG. 1;

FIG. 3 is a side view thereof taken from the right side of FIG. 1;

FIG. 4 is an end view thereof taken from the top of FIG. 1; FIG. 5 is an end view thereof taken from the bottom of FIG. 1; and,

FIG. 6 is a back plan view thereof.

The broken line showing of the right side of a carrying case is for illustrative purposes only and forms no part of the claimed design.
